LOUIS N. D. WILLIAMS
BY HIS ATTORNEY
Harry Sweet

UNITED STATES PATENT OFFICE.

LOUIS N. D. WILLIAMS, OF OGONTZ, PENNSYLVANIA.

FACILITATING THE MECHANICAL TRANSFER OF STITCHES FROM NEEDLES OF KNITTING-MACHINES.

1,344,468.

Specification of Letters Patent. Patented June 22, 1920.

Application filed February 6, 1917. Serial No. 146,887.

To all whom it may concern:

Be it known that I, Louis N. D. Williams, a citizen of the United States, residing in Ogontz, Pennsylvania, have invented 5 certain Improvements in Facilitating the Mechanical Transfer of Stitches from Needles of Knitting-Machines, of which the following is a specification.

The object of my invention is to facilitate the removal of stitches from the needles of a knitting machine by means of transfer points which enter said stitches. This object I attain by expanding the bases of the 10 stitches and thereby increasing the area of the openings for the entrance of the transfer points.

In the accompanying drawing—

Figure 1 is an exaggerated representation of a number of adjoining needles of a knitting machine, the intervening web holders and the corresponding stitches of the terminal course and of two preceding courses, the web holders being shown by full lines in their retracted or releasing position in respect to the sinker wales of the web, and by dotted lines in their normally projected or retaining position, and

Fig. 2 is a similar view showing the web holders projected in advance of their normal retaining position and illustrating the expansion of the bases of the terminal stitches of the web which is thereby effected.

In the drawing, a series of adjoining needles of a knitting machine are represented at 1 and the alternating web holders at 2, stitches of successive courses of adjoining wales of the web being represented at 3, 4 and 5, the stitches 5 being the terminal stitches which are still upon the needles.

In the normal operation of the machine the web holders are retracted to the position shown by full lines in Fig. 1, and then projected as shown by dotted lines until their hooks overlap the sinker wales 6 between the stitches 5 and thereby prevent the rise of said stitches with the needles when the latter are raised so as to clear their latches and present the hooks of the needles in position to receive the fresh knitting yarn.

Under such circumstances the sinker wales 6 are not subjected to tension and the stitches 5 hug the needles 1 to such an extent that the bases of the stitches available for the entrance of the transfer points are 55 of limited area, as shown in Fig. 1, so that in effecting transfer of the stitches it frequently happens that one or more of the transfer points will fail to enter its appropriate stitch, and the latter will be dropped 60 in making the transfer.

I find, however, that if the web holders 2 are, as shown in Fig. 2, projected to an abnormal extent after the terminal course of stitches has been drawn by the needles 1, 65 but before it has been cast therefrom, tension imparted to the sinker wales of the web which are engaged by the web holders will cause said stitch bases to be expanded laterally, as also shown in Fig. 2, thus 70 materially increasing the area for the entrance of each transfer point and correspondingly decreasing the chance of dropping stitches because of the failure of the transfer points to properly enter the same. 75

Such expansion of the bases of the stitches upon the needles causes a corresponding spreading and shortening of the loops of the stitches 4 of the preceding course but this is readily permissible as 80 such stitches are not under tension.

I find that even if, after the stitches assume the position shown in Fig. 2, the web holders are withdrawn from their abnormally projected position the stitches 4 and 5 will not again resume the relations shown in Fig. 1, but will retain substantially the relations shown in Fig. 2, at least for such length of time as may be necessary to insert the transfer points into the stitches 5 behind the needles 1, this being especially true if the web holders are a number of times retracted to the position shown by full lines in Fig. 1, and, after each such retraction, are abnormally projected to the 95 position shown in Fig. 2, before engaging the transfer points with the stitches.

It will be evident the same effect will be produced by moving the needles backwardly in respect to fixed web holders, as by moving 100

the web holders forwardly in respect to fixed needles.

I claim:

The mode herein described of preparing 5 the stitches of the terminal course of a knitted web for the entrance of transfer points, said mode consisting in imparting

abnormal tension to the intervening sinker wales, after said terminal course of stitches has been drawn by the needles but before 10 it has been discharged therefrom.

In testimony whereof I have signed my name to this specification.

LOUIS N. D. WILLIAMS.
